CLARENCE J. COBERLY AND ERNEST S. CROASDALE, OF LOS ANGELES, CALIFORNIA, ASSIGNEES TO KOBE INC., OF HUNTINGTON PARK, CALIFORNIA, A CORPORATION OF CALIFORNIA

TAKE-UP DEVICE FOR FLEXIBLE CONDUCTORS

Application filed February 4, 1930. Serial No. 425,840.

This invention relates to a device for holding relatively taut a plurality of conductors which are carried from a stationary member to a movable member. As an illustration of the utility of the present invention, reference is made to the Patent No. 1,585,893, issued May 25, 1926, to Clarence J. Coberly, for a pipe slotting machine. This pipe slotting machine has a movable carriage which is adapted to travel along a length of pipe in which slots are to be cut by oxygen jets. The entire apparatus carried by the carriage includes electric motors for operating small drills by which the pipe is first perforated; heating torches which utilize oxygen and acetylene, or other gases, to pre-heat the pipe previous to the application of jets of oxygen by which to cut slots; cylinder-piston operating devices which utilize air under pressure; and cooling devices which utilize a flow of cold water for keeping the operating parts of the equipment of the carriage at a desired low temperature.

The supplying of requisite mediums to the apparatus or equipment of the carriage requires conductors, such as cables for electric current and flexible tubes or hose for gases and liquids. Our invention comprehends a simple and efficient means for keeping these conductors relatively taut so that there will be no possibility of their becoming entangled, so that they will be at all times out of the way of the workmen and so that the delivery ends of such conductors may readily travel along with the carriage without interfering with the operation of the carriage in any manner whatsoever.

An object of the invention is to provide a take-up device which will automatically compensate for elongation and contraction of the conductors for various reasons which include change in temperature and change in pressure within those conductors employed for carrying fluids under pressure from a control or valve station to a movable carriage or mechanism.

A further object of the invention is to provide a simple and effective sheave construction in which a traveling frame is employed, this traveling frame having a plurality of

relatively movable sheaves thereon and means, such as weights, for applying forces to taunt the respective conductors which are carried around the sheaves.

A further object of the invention is to provide a casing which may be set into the ground so as to form a well, this casing having substantially vertical guide members therein on which the frame of the take-up device may slide during its operation.

Further objects and advantages of the invention will be made evident throughout the following part of the specification.

Referring to the drawing which is for illustrative purposes only,

Fig. 1 is a partly sectioned elevational view showing a utility of the invention.

Fig. 2 is an enlarged horizontal cross section on a plane represented by the line 2—2 of Fig. 1.

Fig. 3 is a horizontal cross section taken principally on a plane represented by the line 3—3 of Fig. 1, but one of the sheaves thereof and its associated mechanism being sectioned as indicated by the line 3a—3a.

Fig. 4 is an enlarged horizontal cross section on a plane represented by the line 4—4 of Fig. 1.

Fig. 5 is an elevational view showing the inner face of a plate member employed in the practice of the invention to form slide members by which sheaves are slidably secured to the frame member of the take-up device.

In Fig. 1 of the drawing we show a casing 11, which may consist of a pipe of suitably large diameter, set into the ground or submerged below a floor 12 in an upright position, which "upright position" is intended to convey the meaning of any position, between vertical and horizontal, of sufficient slope to cause movement by gravity of a take-up device 13 along guides 14 which may be secured longitudinally within the casing in diametrically opposing positions, as shown in Figs. 1 through 4. The take-up device 13, in its simple form constituting a preferred embodiment, consists of a frame 15 having upper and lower substantially horizontal end plates 16 and 17 and slide bars 18 extending substantially vertically between the end

plates and being secured thereto by either nuts 20 applied to threaded ends 21 which project through holes in an end plate such as 16, or cap screws 22 which are extended 5 through an end plate such as 17 into threaded engagement with the ends of the bars 18; a primary loop engaging element or sheave 24 which rotates on a pin 25 extended laterally through a U-shaped bracket 26 which 10 projects downwardly in centralized position from the lower end plate 17; and a plurality of secondary sheaves 27 which are held in slidable relationship to the frame 15 by slide members 28, the end plates 16 and 17 having 15 notches 19 therein which engage the guides 14. As shown in Fig. 3, the bars 18 are arranged in pairs so as to form substantially vertical slides having engagement with grooves 29 in the vertical edges of the slide 20 members 28. As shown in Figs. 3 and 5, the secondary members or slide members 28 which are held in slidable relationship to a primary member formed by the frame 15 each consist of a pair of cooperating side 25 plates 30 which are secured together by bolts 32, shown in Fig. 1, which bolts are extended through holes 33 in the pairs of side plates 30, the heads and nuts of such bolts being received in recesses 34 in the side plates 30, as shown in Fig. 1. Each of the side plates 30, as shown in Figs. 3 and 5, has an annular recess 36 therein adapted to receive a sheave 27, and upwardly extending channels 37 which, when the plates are placed together, cooperate to form openings through which a conductor may be carried to and from a sheave 27. As shown best in Fig. 3, the plates 30, when bolted together, hold a bearing member 38 in proper position to rotatably support a sheave 27 in its enclosing recess 36.

As shown in Fig. 1, a loop 40 of a conductor or flexible member 41 is carried over the primary sheave 24, the upper ends of the 45 loop extending through openings 42 and 43 in the upper and lower end plates 16 and 17, as shown in Figs. 2 and 3, which holes 42 and 43 are preferably situated on a diametral plane extended through the take-up device 50 13. The upper end plate 16 has a plurality of openings 44 therein through which conductors or flexible members 45, 46, 47, 48, 49, and 50 are extended so as to pass around respective secondary sheaves 27, as indicated at 55 in Fig. 1.

It will be perceived that each of the conductors 41 and 45 through 50 extends down into the casing 11 in the form of a take-up loop, such as the loop 40 of the conductor 41 60 and the loop 52 of the conductor 50. Each of these conductors is secured at its leftward end to a stationary structure 55 and is secured at its rightward end to a downwardly projecting part 56 of a carriage 57 having wheels 58 whereby it may move freely

along longitudinal tracks 59. The leftward ends of the conductors are preferably carried around a member 60 having curved channels therein, and sheaves, as indicated at 62 in Fig. 1, may be employed to support the rightward portions of the conductors where they leave the upper end of the casing 11 and turn toward the carriage 57. The conductor 41, extending around the primary sheave 24, carries the weight of such sheave and the frame 15 which is attached thereto. The conductors 45 through 50 each individually support a sheave 27 and the slide member 28 in which such sheave is rotatably supported, the slide member being preferably of metal plates, such as indicated at 30, and thereby serving as a weight associated with the sheave. The depending loop 40 formed by the conductor 41 within the casing 11 is held taut due to the weight of the frame 15, the tautness of this loop 40 being maintained regardless of the length of the loop, which length of loop changes as the carriage 57 is moved on the track 59. In a like manner, the depending loops in the conductors 45 through 50 are each held taut due to the weight of the respective sheaves 27 around which they are carried and the weight of the slide members 28 associated with the sheaves 27. In view of the fact that the sheaves 24 and 27 are relatively movable in vertical direction, each depending loop in a conductor is held taut independently of the remaining loops, this condition prevailing whether the frame 15 and its associated parts are supported in raised or lowered position within the casing 11 in response to movement of the carriage 57 toward one end or the other of the track 59.

The conductor 41 may be an electric cable 105 for conducting electric current to the electrically operated parts carried by the carriage 57, and the remaining conductors 45 through 50 may be lengths of flexible tube or hose through which the various fluids required in the operation of mechanism carried by the carriage 57 may be conducted. The conductors are subject to variation in their length, this resulting from the various causes such as contraction and expansion due 110 to changes in temperature and contraction and expansion due to changes in pressure within those conductors which are in the form of tubular members through which the various liquids and gases are carried from a 115 source of supply, such as the valve 70 of Fig. 1, to connectors, such as indicated at 71, mounted on the downwardly projecting portion 56 of the carriage 57.

It is plainly evident that the depending 120 loops in the various conductors cannot be maintained at a constant length under the conditions in which they are employed, but this change in the length of the various loops is taken care of by the relative movement be- 125

tween the various sheaves 24 and 27 carried by the frame 15. Should the change in length of the conductor 41 be greater than the change in length of the conductors 45 through 50, the change in the length of the loop 40 will cause the frame 15 to move relative to the slide members 28, and should the change in length of one or more of the conductors 45 through 50 be greater than the 10 change in length of the remaining conductors, the sheaves 27 and slide members 28 associated therewith will move on the slides formed by the bars 18 to such relative positions as will compensate for the change in 15 length of these conductors.

Although we have herein shown a simple and practical embodiment of our invention, it is recognized that certain parts or elements thereof are representative of other parts, elements, or mechanisms which may be employed in substantially the same manner to accomplish substantially the same results; therefore, it is intended that the invention shall not be limited to the details disclosed herein but shall have the scope of the following claims.

We claim as our invention:

1. A take-up device of the character described for use in holding taut a plurality of 30 flexible members, including: a movable primary member having a primary loop engaging element for engaging a loop in one of said flexible members; and a plurality of secondary loop engaging elements, said secondary elements being longitudinally movable on said primary member and each engaging a loop in one of the remaining flexible members.

2. A take-up device of the character described for use in holding taut a plurality of 40 flexible members, including: a primary member having a primary loop engaging element for engaging a loop in one of said flexible members; a plurality of secondary loop engaging elements, said secondary elements being longitudinally movable on said primary member and each engaging a loop in one of the remaining flexible members; and means for guiding said primary member for movement in a longitudinal direction with respect to the loops of said flexible members.

3. A take-up device of the character described for use in holding taut a plurality of 55 flexible members, including: a movable frame having longitudinal slides thereon; a primary sheave supported by said frame so as to engage a loop in one of said flexible members; a plurality of movable slide members held in said slides of said frame; and a sheave 60 carried by each of said slide members for engaging a loop in one of the remaining of said flexible members.

4. A take-up device of the character described for use in holding taut a plurality of 65 flexible members, including: a movable

frame; upright guides for said frame; a primary sheave on said frame for engaging one of said flexible members, the weight of said frame holding said flexible member taut; a plurality of slides on said frame; a plurality of slide members working on said slides; and a secondary sheave carried by each of said slide members for engaging loops in the remaining of said flexible members, the weight of each slide member holding its respective loop taut. 70

5. A take-up device of the character described for use in holding taut a plurality of flexible members, including: a movable frame; a casing set into the ground with its upper end near the surface; vertical guides extending within said casing, said guides engaging said frame; a primary sheave on said frame for engaging one of said flexible members, the weight of said frame holding said flexible member taut; a plurality of slides on said frame; a plurality of slide members working on said slides; and a secondary sheave carried by each of said slide members for engaging loops in the remaining of said flexible members, the weight of each slide member holding its respective loop taut. 80

6. A take-up device of the character described for use in holding taut a plurality of 90 flexible members, including: a movable frame; rigid upright guides for determining the movement of said frame; and a plurality of sheaves carried by said frame, one of said sheaves being rotative on an axis stationary relative to said frame, and the remaining of said sheaves being longitudinally movable relative to said frame. 95

7. A take-up device of the character described for use in holding taut a plurality of 100 flexible members, including: a movable frame; rigid guides for determining a longitudinal path of movement of said frame; and a plurality of sheaves carried by said frame, one of said sheaves being rotative on an axis stationary relative to said frame, and the remaining of said sheaves being longitudinally movable relative to said frame. 105

8. A take-up device of the character described for use in holding taut a plurality of 110 flexible members, including: a movable frame comprising a pair of end plates and parallel pairs of bars extending between said end plates; a sheave mounted on said movable frame so as to rotate on an axis which is stationary relative to said frame; a plurality of slide members sliding on said bars; and a sheave carried by each of said slide members. 115

9. A take-up device of the character described for use in holding taut a plurality of 120 flexible members, including: a movable frame; a primary sheave mounted on an axis stationary with respect to said frame; a plurality of secondary sheaves longitudinally movable on said frame; and a weight con- 125

nected to each of said secondary sheaves.

10. A take-up device of the character described for use in holding taut a plurality of flexible members, including: a movable frame; a primary sheave mounted on an axis stationary with respect to said frame; a plurality of secondary sheaves longitudinally movable on said frame; a weight connected to each of said secondary sheaves, said frame serving as a weight for said primary sheave; and rigid guides for said frame.

11. A take-up device of the character described for use in holding taut a plurality of flexible members, including: a movable frame; a primary sheave mounted on an axis stationary with respect to said frame; a secondary sheave longitudinally movable on said frame; a weight connected to said secondary sheave, said frame serving as a weight for said primary sheave; and rigid guides for said frame.

In testimony whereof, we have hereunto set our hands at Los Angeles, California, this 31st day of January, 1930.

CLARENCE J. COBERLY.
